UNITED STATES PATENT OFFICE.

WALTER S. MCGUIRE, OF SHADYSIDE, OHIO.

FLASH-LIGHT.

1,130,529.

Specification of Letters Patent.

Patented Mar. 2, 1915.

Application filed May 13, 1914. Serial No. 389,310.

To all whom it may concern:

Be it known that I, WALTER S. MCGUIRE, a citizen of the United States, and a resident of Shadyside, in the county of Belmont and State of Ohio, have invented a new and Improved Flash-Light, of which the following is a full, clear, and exact description.

My invention relates to flash lights employed in photography.

10 An object thereof is to provide a simple, efficient and automatic contrivance whereby the intensity of the light produced by the flash can be modified by reflectors and screens.

15 Another object of the invention is to provide a flash light of the character described which has a source of light for indicating the light effect that the flash will produce when set off.

20 A further object of the invention is to produce a flash light of the character described wherein the product of combustion resulting from the flash is prevented from forming a cloud and thus diminish the effect 25 of the flash.

With the above and other objects in view, the nature of which will more fully appear as the description proceeds, the invention 30 consists in the novel construction, combination and arrangement of parts as herein fully described, illustrated and claimed.

In the accompanying drawings forming part of the application, similar characters of reference indicate corresponding parts 35 in all the views and Figure 1 is a front elevation of a flash-light cabinet embodying my invention, Fig. 2 is a perspective view of the same showing the exterior diffusing screen partly raised; Fig. 3 is a perspective 40 view of the contrivance from the rear thereof; Fig. 4 is an enlarged fragmentary rear view of the lower part of the cabinet showing the door open and illustrating the attachment carried by said door; Fig. 5 is a front 45 elevation in perspective of the flash light with the side reflectors removed; Fig. 6 is a vertical section on line 6—6, Fig. 1; Fig. 7 is an enlarged section of the powder pan and the holder therefor; Fig. 8 is a section 50 view of the union whereby the air from the controlling bulb is led to the shutter and the flash light; and Fig. 9 is a diagrammatic view showing the air connection and the electric connections used for the operation 55 of my flash light.

Referring to the drawings, 10 represents

a cabinet of any suitable material, which is provided with an inclined glass front 11, the inclination being such that the cabinet converges toward the bottom thereof. The 60 front of the cabinet is preferably formed of two parts, the lower part being removable. A roller screen 12 is secured to the front of the cabinet adjacent the bottom thereof so that the glass front can be screened partially or totally by manipulating a chain 13 controlling the position of the roller screen 12. The cabinet 10 is mounted to slide vertically in a frame 14, the posts 15 of which have grooves engaged by members 70 16 provided on the parallel sides of the cabinet 10. A locking mechanism (not shown in the drawing) is provided whereby the cabinet can be adjusted in any desired position in said frame 14. A bracket 17 is provided within the cabinet 10, adjacent the bottom thereof, forming a support for a lamp 18. In line with the flame of the lamp is a support 19 carried by a door 20 provided in the lower rear part of the cabinet 80 10 and movable therewith. The support 19 projects exteriorly and interiorly of the door, the interior end carrying a powder pan 21 removably associated with the support. Projecting into the pan 21 and forming part of the support is a nozzle 22 connected, by a passage 23 provided within the support 19, with a nozzle 24 secured to the outer end of the support 19.

The cabinet 10 is provided with a partition 25 extending from substantially the middle of the rear of the cabinet to the upper front corner of the casing. This partition divides the cabinet into two parts A and B, of which part A of the cabinet is 90 the flash-light chamber, and the part B the smoke chamber. The chamber B is provided with a motor-driven fan 26 which is adapted to direct the product of combustion from the chamber B out to an outlet 100 27 of said part B of the cabinet 10. The part A of the chamber is provided with mirrors adapted to reflect the rays of the flash through the glass front 11 of the cabinet 10. One of the mirrors 28 is carried by the 105 partition 25, while the other mirrors 29 are secured to the parallel sides of the cabinet 10 and converge from the front toward the rear of the cabinet; thus, the three mirrors form top and side reflectors for the flash 110 formed in the part A of the cabinet B.

The members 16 of the cabinet are pro-

vided with a bracket 30 positioned below the bottom of the cabinet, which bracket carries a roller screen 31. The roller screen 31 is operable by means of a chain 32 passing through blocks 33 carried by a white reflector 34, which reflector extends from the top of the cabinet and which is adjustable thereon, *i.e.*, the overhanging end of the reflector 34 may not only be moved to and from the front of the cabinet, but the inclination of the same to the front may be varied by changing the engagement of the chain 35 associated with the reflector and the hook 36 provided on the rear of the cabinet. The bracket 30 also carries shading screens 37, each of which extends through half of the width of the cabinet, as best seen in Fig. 1. Each of said shade screens is adjustable on its roller by a chain 38 passing over blocks 39 carried by the white reflector 34. The links of all of the chains for the screens are adapted to engage a hook 40 provided on the bracket whereby the screens can be maintained in any desired position and whereby different degrees of illumination can be obtained.

In addition to the white top reflector 34, side reflectors 41 are provided which are of substantially triangular shape, having one side adjacent the top reflector 34 and the opposite vertex resting on the bracket 30. The side spaces left between the frame of cabinet 10 and the side reflectors 41 is occupied by an unstretched reflector 42. The reflectors 41 and 34 are stretched on frames, and all the reflectors are mounted to be easily removed from or secured to the cabinet 10.

The front of the cabinet on the exterior side is provided with a series of lamps 43, which, as can be seen from the drawings, are within the reflectors and the screens provided about the front of the cabinet, by means of which screens and reflectors the light coming from said lamps can be properly adjusted so as to obtain the desired effect on the subject to be photographed. When the desired effect is obtained, the flash can be set off, and its lighting effect on the object will be substantially the same as that of the lamps but of different intensity. The flash is produced by means of a bulb 44 with which the shutter of the camera 45 is operated. The tube leading from the bulb to the shutter is branched out by providing a Y-shaped union 46, one branch of which is connected to the nozzle 24 by a suitable conduit 47. The branch leading to the nozzle has a restricted opening so as to retard the flow of air from the bulb to the powder pan 21. The nozzle 22 is also a restricted passage which will further retard the flow of air from the passage 23 of the support 19 to the powder pan. The reason for restricting the passages in the branch of the Y-shaped union and in the nozzle 22 is to cause the op-

eration of the shutter of the camera 45 previous to the displacement of the powder from the pan 21 toward the flame of the lamp 18.

Simultaneously with the setting off of the flash the fan motor 48 is brought into a circuit normally kept open by a cotton thread 49. The spool 50 which carries the cotton thread is mounted on a bracket 51 carried by the door 20. The thread from the spool passes through a guide 52, therefrom through notches 53 provided in the side adjacent the front of the powder pan, therefrom it comes in engagement with the end of a movable contact 54 of the switch and then through an eye, from where the thread leads to a retaining device 55, which permits the thread to maintain the movable contact 54 away from the stationary contact 56. The movable and the fixed contacts, as well as all the means for guiding the thread, are provided on the door 20 of the cabinet. The movable contact 54 is, furthermore, so arranged that when the door 20 is opened, the circuit leading to the motor 48 is broken, as the contact between the movable contact 54 and the stationary contact 57 provided within the cabinet 10 is interrupted, as best shown in Fig. 4, although it is in engagement with the stationary contact 56. When the flash is set off, the cotton thread 49 is ruptured, leaving the movable contact 54 to drop or come to engagement with the stationary contact 56, thus setting the motor 48 in motion; consequently, the action of the fan 26 and the setting off of the flash are simultaneous and thereby the formation of a cloud of smoke is prevented within the part A of the cabinet 10. It will also be noted that my cabinet can be used as an ordinary flash by removing the white reflectors provided on the sides and the top of the cabinet and therewith the shading screens and also the diffusing screen 31, leaving the diffusing screen 12 at the glass front.

The provision of the mirrors 28 and 29 increases greatly the effect of the flash by directing the rays through the glass front and toward the white reflectors. If desired my cabinet may be used without the side reflectors by utilizing the top reflector and all the screens. The provision of the lights 43 on the glass front of the cabinet permits the correct adjustment of the light effects that will be obtained by the flash, as the said lights, as previously stated, are positioned within the reflectors and the screens. It will also be remarked that by retarding the flow of air from the bulb to the powder the shutter is opened before the flash is set off; thus there is no danger of setting off the flash before the operation of the shutter.

From the foregoing description, taken in connection with the accompanying drawings,

ings, the advantage of the construction and operation of the device shown will be readily understood by those skilled in the art to which the invention pertains, and while I have described the principle of operation, 5 together with the device which I now consider to be the best embodiment thereof, I desire to have it understood that the device shown is merely illustrative and that such changes may be made when desired as 10 are within the scope of the appended claims.

Having thus described my invention, I claim as new and desire to secure by Letters Patent:

1. In a flash light, a cabinet having a 15 glass front; a partition in said cabinet dividing the same into two chambers, a lower one and an upper one; means for producing a flash in the lower chamber; ventilating means associated with the upper chamber 20 for eliminating the product of combustion produced by the flash; mirrors within the cabinet for directing the light produced by the flash through the glass front; and movable screens associated with the glass front 25 for varying the intensity of the light produced by the flash.
2. In a flash light, a cabinet having a glass front; a partition within the cabinet 30 dividing the same into an upper and a lower chamber; flash producing means in the lower chamber; ventilating means associated with the upper chamber for eliminating the products of combustion due to 35 the setting off of the flash; means controlling the ventilating means, becoming operable when the flash is set off; reflectors within the cabinet for directing the light to the glass front; movable screens associated 40 with the glass front for varying the intensity of the light; and canvas reflectors associated with said screen and glass front substantially as and for the purpose set forth.
3. In a flash light, a cabinet having a 45 glass front; means for setting off a flash in the cabinet; mirrors for directing the light of the flash through the glass front; a white reflector adjustably mounted on the 50 top of the cabinet; a screen associated with the glass front; a second adjustable screen associated with the cabinet and the white reflector; adjustable shade screens positioned between the said screens; and side 55 reflectors for closing the space between the screens, the reflector and the glass front.
4. In a flash light, a cabinet having a 60 glass front; means for the setting off of a flash in the cabinet; mirrors for directing the light of the flash through the glass front from; a white reflector extending from the 65 top of the cabinet over the front of the same; means for varying the angle the said reflector makes with the front; an adjustable screen mounted at the glass front of

the cabinet; a second adjustable screen in front of the first and spaced therefrom; shade screens between the said screens; and side white reflectors for closing the space between the front top reflector and the 70 screens.

5. In a flash light, a cabinet having a glass front; means for setting off a flash in the cabinet; mirrors within the cabinet for directing the light to the glass front; means 75 for varying the effect and intensity of the light coming from the cabinet; and lamps positioned on the exterior side of the glass front and inclosed within said means for varying the light coming from the cabinet, 80 whereby the desired light effect of the flash is gaged from said lamps.

6. In a flash light, a cabinet having a glass front; means for setting off a flash in the cabinet; ventilating means for eliminating 85 the products of combustion resulting from the flash; mirrors within the cabinet for directing the light from the flash to the glass front; adjustable screens and reflectors associated with the glass front for varying 90 the effect and intensity of the light from the flash coming through the glass front; and lamps positioned on the exterior side of the glass front.

7. In a flash light, a cabinet having a 95 glass front; a partition in the cabinet dividing the same into upper and lower chambers; means for producing a flash in the lower chamber; ventilating means in the upper chamber preventing the accumulation 100 of the product of combustion in the lower chamber, said ventilating means becoming operable when the flash is set off; mirrors within the lower chamber for reflecting the light from the flash through the front glass; 105 adjustable screens and reflecting means associated with the cabinet for varying the effect and the intensity of the light coming through the front glass; and lamps positioned on the exterior side of the front 110 glass, substantially as and for the purpose set forth.

8. In a flash light, a cabinet having a glass front; a partition in said cabinet dividing the same into an upper and a lower 115 chamber; a door for said lower chamber in the rear of the cabinet; a powder support associated with said door; a flame generated within said lower chamber; means for forcing the powder from the support to the 120 flame whereby the flash is set off; ventilating means associated with the upper chamber of the cabinet preventing the product of combustion of the flash from accumulating in the lower chamber; an electric motor 125 for actuating said ventilating means; a circuit for the motor; a gravitationally operable switch in the circuit; a thread maintaining said switch normally open, said thread being associated with the powder 130

- support and adapted to be ruptured by the setting off of the flash, whereby said switch is closed, thus setting the ventilating means into operation; mirrors in the lower chamber for directing the light of the flash through the glass front; and adjustable means associated with the cabinet for varying the effect and the intensity of the light coming through the glass front.
10. 9. In a flash light, a cabinet having a glass front; a partition dividing the cabinet into an upper and a lower chamber; a door for the lower chamber in the rear of the cabinet; a powder support carried by the door; electrically actuated ventilating means associated with the upper chamber for eliminating the products of combustion from the lower chamber; a gravitationally operable switch controlling said ventilating means; a cotton thread engaging said powder support and said switch whereby normally said ventilating means are in operative position, said thread being adapted to be ruptured by the setting off of the flash, whereby said switch becomes operable and therewith said ventilating means; a second normally closed switch adapted to be opened when said door is opened, thereby stopping the action of said ventilating means; mirrors associated with the lower chamber; and adjustable reflectors and screens associated with said cabinet for varying the effect and intensity of the light coming through the glass front of the cabinet.
10. In a flash light, a cabinet having a glass front; flash-producing means in the cabinet; mirrors in the cabinet for directing the light of the flash through the glass front; adjustable reflectors and screens associated with the glass front of the cabinet for varying the intensity and the effect of the light passing through the front glass; and lamps positioned on the exterior side of the glass front and inclosed by said reflectors and screens, whereby the probable light effect of the flash can be gaged.
- In testimony whereof I have signed my name to this specification in the presence of two subscribing witnesses.

WALTER S. McGUIRE.
